TOBACCO PIPE

Filed Feb. 29, 1924

FIG. 1.

FIG. 2.

FIG. 4.

Inventor:
Herbert N. Nute

By G. N. Goddard, Atty.

UNITED STATES PATENT OFFICE.

HERBERT N. NUTE, OF BROOKLINE, MASSACHUSETTS.

TOBACCO PIPE.

Application filed February 29, 1924. Serial No. 696,051.

This invention relates to tobacco pipes and is intended to provide a construction and arrangement adapted to produce effective aeration of the pipe stem without impairing its draft or drawing qualities, while making simple and convenient provision for the collection of condensed moisture and for easily and conveniently cleaning the pipe.

Heretofore it has been proposed to provide tobacco pipes with air passages or inlets for the purpose of cooling the smoke and condensing the volatilized constituents of the tobacco, but such proposed constructions have not been satisfactory in use because, as arranged, they impair the drawing qualities or draft, making the pipe difficult to smoke, and because they fail to eliminate the strong or stale flavor of the pipe which many smokers find objectionable. The tendency to clog the passages was a further unsatisfactory consequence of such proposed constructions.

It is the object of the present invention to so construct the stem of the pipe as to largely condense the volatile constituents of the tobacco but without impairing the drawing qualities of the pipe, and at the same time make provision for easy and complete access to the cooling and condensing chamber to permit thorough and easy cleansing of the pipe.

With such ends in view the invention consists primarily in providing the stem of the pipe with an intermediate condensing or cooling chamber without affording any obstacle or impediment to the main smoke-laden current passing from the bowl to the mouth, while admitting fresh air in said chamber as an induced current entering said chamber in the opposite direction to that of the moving column of smoke, and coming into contact with said smoke column in a manner that tends to partially cool the smoke column which it surrounds but without appreciably diverting said column from its direct rearward course to the mouth. This provision of a condensing and cooling chamber arranged to allow direct passage of a smoke column through it, while subjecting said column moving across the chamber to the cooling action of a fresh air current, and that without making the pipe difficult to smoke because of impeded or diminished draft, is the principal feature of this invention.

By making the chamber in the bit or de-

tachable section of the stem, which is usually made of hard rubber, or non-absorbent material, and locating it so that it is readily cleansed after removal of the bit, absorption of the condensing moisture is largely prevented and the pipe may be kept sweet indefinitely instead of acquiring a stale taste.

These and other features of the invention will be particularly explained in the following specification and will be defined in the claims hereto annexed.

In the accompanying drawings I have illustrated a construction and arrangement embodying the principles of this invention, in which:

Figure 1 is a longitudinal central section through the bowl of the pipe and the stem.

Figure 2 is a transverse section on the plane indicated by sectional line 2-2 of Figure 1.

Figures 3 and 4 are similar cross sections through the stem on the planes 3-3 and 4-4 Figure 1, as viewed from the rear or mouth piece end of the pipe in the direction of the sectional line arrows.

The bowl member 1, with its rearward extension 2 usually called the shank, centrally bored to form an air duct 2^a, is of usual and well known construction, and is provided at its rear end with a counterbore to receive the tenoned or reduced forward end 4 of the bit 3. The reduced forward end or tenon 4, leaves an annular shoulder 5 abutting snugly against the rear end of the extension 2 of the bowl member so as to make a tight joint therewith.

The detachable stem member or bit has a bore 6 extending from the rear end or mouth-piece, forwardly to the duct 2^a to form an air or smoke duct through which the smoke is inhaled and expelled alternately.

In the forward end of the stem is formed a cooling and condensing chamber 7, which, as here shown, is in the form of a sector in cross section, the tenon being cut away from its bottom side up to the line of the duct 6, so that the air duct of the bit merges with the chamber at the forward end 105 whereby any moisture flowing from the mouth-piece must drop into the chamber 7 which forms a trap. The rearward extension 8 of the trap is separated by the partition 8^a, from the draft duct or passage 110 and is carried back well toward the mouth-piece to form a pocket, having no direct

communication with the adjacent or over-lying portion of the air duct, but having an external vent 9 extending through the end wall or shoulder 10, formed by reducing the thickness or vertical diameter of the mouth-piece portion of the stem.

When the mouth-piece or bit 3 is tightly jointed to the shank 2 of the bowl member the forward open end of the chamber 7 is closed except for the communication through the smoke duct 2^a in the shank. Saliva can not cross the gap formed by the recess or chamber 7 since gravity will cause it to drop to the bottom of the chamber. The moisture can not, therefore, flow into the bowl nor can it clog the longitudinal air duct of the pipe. The air vent 9, which is materially smaller in cross section than the air-duct or passage 8, allows a gentle inflow of fresh air forwardly in the pipe from the air vent 9 when suction is applied to the mouth-piece with the consequence that an inflowing current of cool fresh air meets and surrounds the rearwardly moving column of smoke from the bowl, thereby causing a partial precipitation or condensation of the volatilized constituents of the smoke which drop to the bottom of the chamber 7 out of the way of the rearwardly moving suction-induced column of smoke. The fresh air duct or passage 8 is of such relatively large diameter in comparison with the inlet air vent hole 9, that the fresh air flows in well above any moisture that may accumulate in said passage.

It will, therefore, be seen that both the fresh air inlet passage and the entire smoke passage are kept free and unobstructed and that the gentle induced forwardly moving current of fresh air encounters the oppositely moving smoke column without interfering with the rearward moving of the latter while at the same time, by its presence, acting to partially cool the smoke and condense a substantial portion of its volatilized constituents.

As the cooling and condensing chamber is located in the forward end of the bit it is obvious that removal of the bit exposes the whole interior of the air chamber and air passage, which thus becomes easily accessible for thorough cleansing. The arrangement of the small air vent or inlet is such as to have no material effect in weakening the draft of the pipe and the chamber does not interfere with the direct rearward flow of the suction-induced air current. The conse-

quence is that, without impairing the drawing qualities of the pipe, the hot smoke from the bowl is tempered and robbed of its harmful constituents while the pipe can readily be kept sweet and clean.

What I claim is:

1. An aerated tobacco pipe embracing in its construction a bowl having a longitudinally bored shank forming a smoke duct, a longitudinally bored bit detachably jointed to the rear end of the shank to form an enlarged condensing chamber affording direct communication between the bore of the shank and the bore of the bit intermediate of said bores, said bit having an aerating passage having a relatively small air inlet orifice at its rear end and opening forwardly into said condensing chamber whereby a current of air, drawn through said passage, enters said chamber from the opposite direction to that of the entering column of smoke and partially cools the smoke without materially interfering with the passage of the smoke through said chamber to the bit.

2. A tobacco pipe embracing in its construction a bowl and its rearward shank longitudinally bored to form a smoke duct, a bit detachably jointed to the rear end of said shank and longitudinally bored to provide a continuation of the smoke duct in the shank, said bit having its forward end recessed to form an enlarged condensing chamber whose bottom is located at a substantial distance below the level of the smoke duct of the shank to prevent flow of accumulated liquid into the shank bore and bowl, said bit being also provided with a longitudinal fresh air inlet passage for conducting a limited supply of fresh air to said condensing chamber from a rearwardly disposed constricted inlet orifice.

3. An aerating bit adapted to be attached to the shank of a tobacco pipe, said bit having its front end hollowed to form a relatively large open chamber and provided with a longitudinal smoke duct extending from the rear of said chamber to the mouth end of the bit, said bit being also provided with an underneath air inlet passage extending in substantial parallelism with said smoke duct and provided, at its rear end, with a relatively small inlet orifice for the admission of fresh air to said chamber when suction is applied to the rear end of the bit.

In witness whereof, I have subscribed the above specification.

HERBERT N. NUTE.
